(57) **CLAIM**

The ornamental design for an underwater LED bulb, as shown and described.

DESCRIPTION

FIG. 1 is a perspective view of the underwater LED bulb;
FIG. 2 is a top plan view of the underwater LED bulb according to FIG. 1;
FIG. 3 is a front elevational view of the underwater LED bulb according to FIG. 1;
FIG. 4 is a bottom plan of the underwater LED bulb according to FIG. 1; and,
FIG. 5 is a side elevational view of the underwater LED bulb according to FIG. 1.

1 Claim, 3 Drawing Sheets

FIG.1.

FIG.2.

FIG. 3.

FIG. 4.

FIG. 5.
